(57) **CLAIM**

The ornamental design for a nail appliqué, as shown and described.

DESCRIPTION

FIG. 1 is a top front perspective view of a nail appliqué showing my new design, the line shading and stippling illustrate contrasting appearances;

FIG. 2 is a top plan view thereof;

FIG. 3 is a right side elevation view thereof, the left side being a mirror image;

FIG. 4 is a front elevation view thereof, the rear being a mirror image;

FIG. 5 is a top front perspective view of an alternative embodiment of a nail appliqué showing my new design, the line shading and stippling illustrate contrasting appearances; FIG. 6 is a top plan view of the nail appliqué shown in FIG. 5; FIG. 7 is a right side elevation view of the nail appliqué shown in FIG. 5, the left side being a mirror image;

FIG. 8 is a front elevation view of the nail appliqué shown in FIG. 5, the rear being a mirror image;

FIG. 9 is a top front perspective view of another alternative embodiment of a nail appliqué showing my new design, the line shading and stippling illustrate contrasting appearances;

FIG. 10 is a top plan view of the nail appliqué shown in FIG. 9;

FIG. 11 is a right side elevation view of the nail appliqué shown in FIG. 9, the left side being a mirror image;

FIG. 12 is a front elevation view of the nail appliqué shown in FIG. 9, the rear being a mirror image;

FIG. 13 is a top front perspective view of yet another alternative embodiment of a nail appliqué showing my new design, the line shading and stippling illustrate contrasting appearances;

FIG. 14 is a top plan view of the nail appliqué shown in FIG. 13;

FIG. 15 is a right side elevation view of the nail appliqué shown in FIG. 13, the left side being a mirror image; and,

FIG. 16 is a front elevation view of the nail appliqué shown in FIG. 13, the rear being a mirror image.

The bottom view (not shown) forms no part of the claimed design.

The broken line showing of the finger is included for the purpose of illustrating environment and forms no part of the claimed design.

1 Claim, 4 Drawing Sheets
